UNITED STATES PATENT OFFICE.

GEORGE A. FREDENBURGH, OF PAWTUCKET, RHODE ISLAND.

THREAD-DRESSING MACHINE.

SPECIFICATION forming part of Letters Patent No. 702,786, dated June 17, 1902.

Application filed January 7, 1902. Serial No. 88,804. (No model.)

To all whom it may concern:

Be it known that I, GEORGE A. FREDENBURGH, a citizen of the United States, residing at the city of Pawtucket, in the county of Providence and State of Rhode Island, have invented certain new and useful Improvements in Thread-Dressing Machines, of which the following is a specification.

Like numerals indicate like parts.

10. Figure 1 is a partial front elevation of my improved thread-dressing machine. Fig. 2 is a continuation of Fig. 1, showing the upper portion of the machine in front elevation. Fig. 3 is a side elevation of the upper portion 15 of the machine shown in Fig. 2. Figs. 4, 5, and 6 are detail views of a modified construction of the ironer-spoils. Fig. 7 is a top plan view of my machine. Fig. 8 is a top plan detailed view, on an enlarged scale, showing the 20 clutch-gearing for one series of twisters as seen on line *a a* of Fig. 9. Fig. 9 is a vertical transverse sectional view of the twister-driving mechanism as seen on line *b b* of Fig. 8. Fig. 10 is a vertical view of my machine 25 in cross-section as seen on line *c c* of Figs. 1 and 2. Fig. 11 is a top plan sectional view of said machine as seen on line *d d* of Fig. 10. Fig. 12 is a top plan view in detail of the means for producing a tension on the thread 30 between the twisters and cylinders. Fig. 13 is a top plan view in detail of one series of twisters. Fig. 14 is an enlarged side elevation of a twister comprising a part of my invention. Fig. 15 is a central sectional view 35 of the same as seen on line *e e* of Fig. 14. Fig. 16 is a central sectional view of the same as seen on line *f f* of Fig. 15. Fig. 17 is a top plan view of the same as seen on line *g g* of Fig. 16. Fig. 18 is a top plan view of the 40 parts below *h h* of Fig. 14 as seen on said line. Fig. 19 is a top plan central sectional view of the ironing devices of my said machine. Fig. 20 is an enlarged cross-sectional view as seen on line *i i* of Fig. 19. Fig. 21 is an enlarged 45 cross-sectional view as seen on line *j j* of Fig. 19. Fig. 22 is a top plan central sectional view of the brush-cylinder. Fig. 23 is a cross-sectional view as seen on line *k k* of Fig. 22. Fig. 24 is an enlarged central longitudinal 50 sectional view of one of the brushes of the brush-cylinder. Fig. 25 is a central cross-sectional view of the same. Fig. 26 is a top plan

sectional view of the trip-lever for immersing the thread in the sizing-trough. Fig. 27 is a side elevation of said lever and connected parts as seen on line *l l* of Fig. 26. Fig. 28 is a similar view showing the position of said lever when lifted above the level of the sizing liquid in said trough.

My invention is a thread-dressing machine, 60 and it consists of the novel construction and combination of the several parts, as herein-after particularly described, and specifically set forth in the claims.

The object of my invention is to provide a 65 compact machine which is capable of sizing, drying, and polishing the thread while it is twisting and at the same time greatly increasing the product of such machines.

In the drawings, 1 represents the frame of 70 the machine to support the operating parts. In proper bearings are mounted the journals of three pulleys 2, 3, and 4. A belt 5 from the pulley 2 drives the pulley 6, properly mounted on a bracket from the frame 1. A 75 belt 7 from the pulley 2 drives the pulley 8 on one end of the brush-cylinder, and a cross-belt 9 from a pulley in line with the pulley 2 on the same shaft drives a pulley 8^a of the brush-cylinder on the shaft of said brush cylinder at 80 the opposite end thereof. A belt 10 from the pulley 3 drives the pulley 11 of the lower ironing-cylinder, and a cross-belt 12 from a pulley in line with the pulley 3 on the same shaft drives a pulley 11^a of the ironing-cylinder 85 on the shaft of said lower ironing-cylinder at the opposite end thereof. A belt 13 from the pulley 4 drives the pulley 14 of the upper ironing-cylinder, and a cross-belt 15 from a pulley 16 in line with the pulley 4 on 90 the same shaft drives a pulley 17 of the upper ironing-cylinder at the opposite end thereof. On the upper shaft concentric with the pulley 4 is a pulley 18, and a belt 19 from the pulley 18 drives a pulley 20, which is mounted on a 95 standard 21 at the top of the machine.

The thread to be glazed and polished by my said machine is wound on spools or bobbins 22, which are mounted, respectively, on spindles 23.

On each side of the machine is a trough 24, containing a suitable sizing liquid. On the front of each trough 24 is a bracket 25, supporting a rod 26, and the thread unwound

from the spool 22 passes over said rod 26 down into the said liquid. In each trough 24 is pivotally mounted on a rod 27 a lever 28, having its upper end above the upper edge 5 of said trough and slightly bent and flattened, as shown, and provided at its lower bent end with a peripherally-grooved wheel 29, around the under side of which the thread 30 passes, as best shown in Fig. 10. This lever 28 and its connected parts are fully shown in the enlarged detail views of Figs. 26, 27, and 28, where it is seen that said lever 28 has a hub 31, by which it is mounted loosely on the rod 27. A collar 32 is held on the rod 27 15 by a set-screw 33 and serves to prevent lateral movement of the hub 31, which abuts said collar 32. A collar 34 is mounted on the rod 27 and abuts the hub 31 on the opposite side. The collar 34 is held in position by the 20 set-screw 35, and said collar has a projection of less diameter which enters the contiguous open end of the hub 31. A spiral spring 36 is in a concentric chamber of the hub 31 and has one end thereof in contact with the end 25 of the projection of the collar 34 and the other end in contact with an internal shoulder in the hub 31. There is a wedge-shaped projection 37 from the side of the collar 32, and the same enters a slot on the adjacent 30 edge of the hub 31 as the lever 28 is turned, thus locking the parts together when in the position illustrated in Figs. 10 and 27.

The thread after it has been saturated in the sizing liquid of the trough 24 passes up 35 through the lower twisting mechanism, and this mechanism is thrown into and out of operation by a shipper and gearing, which I will now describe. This twisting device is shown in Figs. 7, 8, 9, 10, 11, 13 to 18, inclusive. On a rod or shaft 39 is mounted the pulley 6. On a bracket 40, bolted at 41 to the frame 1, is a vertical tubular bearing 42, in which is rotatably mounted a shaft 43. A gear 44 and beveled gear 45 in one piece are 40 mounted on the shaft 43. A shipping-lever 46 is pivotally mounted at 47 upon the bottom of a stand 48, which extends down from the bracket 40. A fixed collar 49 is secured in place upon the shaft 39 by the set-screw 50. A beveled gear 52 is slidably mounted 45 on the shaft 39 and has a hub 53 with a peripheral groove in which the shipping-lever 46 is supported. The beveled gear 52 is movable by the shipping-lever 46 into and out of 50 engagement with the beveled gear 45. The beveled gear 52, though slidable on the shaft 39, is splined or otherwise secured thereto, so as to revolve with it; but when the beveled gear 52 is by the shipping-lever 46 moved 55 out of engagement with the beveled gear 45 the latter does not revolve; but when the beveled gear 52 is moved by the shipping-lever 46 into engagement with the beveled gear 45 the latter is revolved. The revolution of the 60 beveled gear 45 causes the gear 44, which is integral therewith, to revolve also, and the gear 44 by engagement with the gears 54 and

55 causes the revolution of the gears 56, 57, 58, 59, and 60, which are in mesh with said gears 54 and 55. The result of this arrangement is that the gears 45, 56, 57, 58, 59, and 60 all rotate in the same direction, as indicated by the arrows thereon in Fig. 8.

Each one of the gears 56, 57, 58, 59, and 60 operates a twister, said five twisters being 70 arranged in a series, as seen in Figs. 1, 7, 10, and 13. In Figs. 14 to 18, inclusive, are shown enlarged detail views of each twister.

On the bracket 40 is mounted a fixed beveled gear 61. A vertical shaft 62 has a concentric circular disk 63, by which it is supported upon the upper plane surface of the fixed beveled gear 61. The shaft 62 extends down through a tubular bearing 64 of the bracket 40 and has at its bottom a gear, (one 80 of those designated as 56, 57, 58, 59, and 60, say, in Figs. 14, 15, and 16.) This gear is designated as 56.

Two standards or uprights 65, integral with the disk 63, extend up therefrom. These standards are slotted, as indicated in Fig. 15, and have bearings in which is mounted the shaft 66 of the beveled gear 67, which meshes with the fixed beveled gear 61. A set-screw 68 through the hub 69 of the beveled gear 67 fastens it to the shaft 66. A roller 70 is fastened on the shaft 66. A roller 71, fastened on a journal 72, is rotatably mounted in the slots of the standards 64 95 65 and rotates by its frictional contact with the roller 70. A block 73 fits into these slots to close the outer opening thereof and is held in place by the set-screws 74 75. A cap-piece 76, having a central flaring opening 77, is fastened by screws 78 to the tops of the 100 standards 65.

The fixed beveled gear 61 has a hub 79, and a set-screw 80, passing through the hub 79, secures it in place upon the shaft 62. The lower portion of the tubular bearing 64 below 110 the bracket 40 has a horizontal slot or opening 81, as shown in Fig. 14. A sleeve or tube 82 loosely surrounds the shaft 62, Figs. 15, 16, 18, and is provided with a handle 83, which projects out through the radial slot 115 or opening 81. The sleeve 82 has a longitudinal slot 84. The vertical shaft 62 has a longitudinal slot 85. The gear 56, tubular bearing 64, hub 79, beveled gear 61, and disk 63 have each a radial slot, as illustrated in 120 Figs. 14, 15, 16, and 18.

When the handle 83 is in the position indicated by dotted lines in Fig. 18, its slot 84 is in line with the other slots last above mentioned, so that a thread may be passed 125 through all said slots to a central position, and then by moving the handle 83 to the position shown in solid lines in Fig. 18 the thread is confined to a vertical movement through the slot 85 of the vertical shaft 62.

The rotation of the gear 56, derived, as already explained, from the shaft 39, (when the shipping-lever 46 has thrown the beveled gear 52 into engagement with the beveled

gear 45,) causes the rotation of the vertical shaft 62 and its standards 65. This rotation of the standards 65 causes the beveled gear 67, which is mounted therein, to move around the fixed beveled gear 61, and the rotation of the shaft 66 so caused compels the rotation of the rollers 70 and 71 in the direction indicated by the arrows in Fig. 15.

As the thread 30 passes through the twister 10 centrally and between the rollers 70 71 and out of the thread-hole 77 of the cap-piece 76 it is properly twisted by said passage. After leaving the twisting mechanism just described the thread next passes over a tension device shown in Figs. 1 and 10 and in enlarged detail in Fig. 12 and described as follows: On the frame 1 a plate 86 is bolted, which has three long brackets or arms 87, 88, and 89, each ending in a head which has an aperture rectangular in cross-section. Tension-bars 90, 91, and 92 are mounted on said brackets 87, 88, and 89, respectively, each having at its outer end two grooved tension-wheels 93, rotatably mounted thereon, and each tension-bar has a shank rectangular in cross-section, which is inserted adjustably in said aperture of the head of each bracket, and a set-screw holds the tension-bar in its adjusted position, thereby insuring a regulated tension for the thread, which passes between the tension-rollers, as shown in Figs. 1 and 10. Intermediate short bracket-arms extend from the plate 86 between the longer brackets, as shown in Fig. 12. Each of these intermediate brackets has a head with an aperture therein like those hereinbefore described, and tension-bars are mounted adjustably therein, each having two tension-rollers thereon, all as fully illustrated in Fig. 12. From this tension device the thread next passes to a brushing device, shown in Figs. 1 and 10, and in enlarged detail views in Figs. 22, 23, 24, and 25 and described as follows: On the frame 1 are standards 94 95, bolted thereto and having tubular bearings 96 97 on their upper ends. A shaft 98 has its two ends formed into pipes 99 100, respectively. At the closed bottom of each of these pipes is a vent or hole passing through the side of the pipe, as plainly seen in Fig. 22. On the pipe 99 is mounted a steam-cylinder 101, having a tubular hub or extension 102, the exterior surface of which in a portion thereof is in loose contact with the interior surface of the tubular bearing 97. The pulley 8 is also mounted fast upon the pipe 99. A steam-pipe 103 of the same diameter and bore as the pipe 99 is loosely inserted in the end of the hub or extension 102 of the steam-cylinder, and its inner end abuts the outer end of the pipe 99, as shown in Fig. 22. A stuffing-box 104 surrounds the outer peripheral end of the hub or extension 102 and said pipe 103, and a coupling 105 unites the pipe 103 to a steam-pipe 106. On the open end of the steam-cylinder 101 is an outwardly-extending annular flange 107, and abutting it and fastened thereto is a circular

disk 108, having a central aperture to allow the passage of the shaft 98 through it. This disk 108 has an integral tubular hub 109, and on the opposite end of said tubular hub 109 is another disk 110, integral with it and having a central aperture for the passage of the shaft 98 through it. A steam-cylinder 111 has an outwardly-extending annular flange 112 bolted to the disk 110 and is provided with a central aperture. The pulley 8 has a long tubular hub 113, loosely mounted on the pipe 100 and passing through the central aperture of the cylinder 111, and said hub is supported by the tubular bearing 96 of the bracket 94. A steam-pipe 114 is connected by a coupling 115 to a short pipe 116, whose inner end abuts the outer end of the pipe 100. A stuffing-box 117 is mounted on the pipe 116, and a stuffing-box 118 is mounted on the hub 113 and is bolted to a central hub 119 of the cylinder 111. Four steam-pipes 120, 121, 122, and 123 are mounted rotatably in holes made therefor in the disks 108 and 110. In the cylinder 111 these pipes have closed ends, but are provided each with a vent or opening, as seen in Fig. 22. These disks 108 and 110 each have four tubular projections or bearings for the support of said four steam-pipes 120, 121, 122, and 123, and stuffing-boxes 124 are secured on said hubs. Said four steam-pipes have open ends extending into the cylinder 101.

On each of the steam-pipes 120, 121, 122, and 123 is fastened a tubular brush-block 125, having bristles 126 arranged in bunches, and the end of each block 125 is concentrically tapered to receive a cap 127, as seen in Fig. 24.

On the end of each of the pipes 120, 121, 122, and 123 is a gear, those shown in Fig. 22 being designated as 128 and 129, and these four gears are driven by a central gear 130, which is fastened to the hub 113 of the pulley 8.

The belts 7 and 9, passing over the pulleys 8 and 8^a, cause the steam-cylinders 101 and 111 to rotate, with their connected parts, and the gear 130, rotating with the same speed and in the same time, causes the rotation of the four gears on the steam-pipe shafts 120, 121, 122, and 123 with a greater speed, because each of the said four gears is of a less diameter than that of the central gear 130, which drives them all. Steam passing up through the pipe 105 goes through the pipes 103 and 99 into the cylinder 101 and thence passes through each of the pipe-shafts 120, 121, 122, and 123 and out of the vents thereof into the cylinder 111 and thence through the hole in the pipe 100, out through the pipe 116, and into and through the pipe 114. From the brushes 125 the thread passes through a tension device exactly like that already described and thence to the ironing-cylinders, which are shown in Figs. 1, 10, and 11 and in enlarged detail views in Figs. 19, 20, and 21 and are described as follows: The steam-pipe 105 is connected by a coupling (or elbow,

as the case may be) 131 to a short pipe 132. The pulley 11 is mounted on an extended hub 133 of a steam-cylinder 134. This hub 133 is supported in the bearing 135 of a bracket 136, 5 which extends from the frame 1. A shaft 137 has its two ends formed into pipes 138 139, each having a vent at the inner or closed end for the passage of steam therethrough. The cylinder 134 at its upper end has an outwardly-extending annular flange 140. The pipe 133 passes through a central aperture in the cylinder 134. A circular disk 141 has a central aperture for the passing of the shaft 137 through it and is fastened to the flange 140 by bolts, as seen in Fig. 19. The disk 141 has an integral tubular shaft 142, through which the shaft 137 passes, and at the opposite end of the tubular shaft 142 is an integral circular disk 143. A steam-cylinder 144, having an outwardly-extending annular flange, is bolted thereto and has a hub 145. The pulley 11^a has a long extended hub 146, which extends into the cylinder 144, and said hub 146 is supported in the bearing 147 of the bracket 148, which extends from the frame 1. The hub 146 is mounted fast on the pipe 130. A short pipe 149 has its inner end abut the outer end of the pipe 139, and said pipe 149 is connected by a coupling (or elbow, as the case may be) 150 to the pipe 114. A stuffing-box 151 surrounds the pipe 149. A stuffing-box 152 surrounds the hub 139 and is connected to the hub 145 of the cylinder 144, and a stuffing-box 153 surrounds the pipe 132. On each of the disks 141 and 143 are six tubular hubs, and on each of these hubs there is a stuffing-box 154. There are six steam-pipes 155, 156, 157, 158, 159, and 160, mounted between the disks 141 and 143, which 35 pass through the tubular bearings of said disks and through holes made in said disks for their passages. Each of these six pipes has an open end opening into the cylinder 134. The opposite ends of said six pipes are closed; but each has a vent opening into the cylinder 144. On each of these six pipes there is a gear 161, and all these are turned by a central gear 162, mounted on the extended hub 146 of the pulley 11^a. On each of these 45 six pipe-shafts a series of ironers 163 is mounted and secured thereto by set-screws, as illustrated in Fig. 19. These ironers 163 have beveled peripheral surfaces. Collars 164 on the said shafts and secured in place by set-screws hold said ironers from lateral movement on their respective shafts. The belts 10 and 12, passing on the pulleys 11 and 11^a, cause the steam-cylinders 134 and 144 to rotate with their connected parts, and the gear 146, rotating with the same speed and in the same time, causes the rotation of the six gears on the steam-pipe shafts 155, 156, 157, 158, 159, and 160 with a greater speed, because each of the said six gears is of a less diameter than 55 that of the central gear 146, which drives them all. Steam passing up through the pipe 1 105 enters through the pipes 132 and 138 into the cylinder 134, and thence passes through the pipes 155, 156, 157, 158, 159, and 160 and out through the vent-holes thereof into the cylinder 144, and thence through the opening in the pipe 139 out through the pipe 114. In Figs. 4, 5, and 6 I show modified forms of these ironers. In Fig. 4 the ironer is cylindrical, in Fig. 5 it has a central V-shaped peripheral groove, and in Fig. 6 a long tube has such peripheral grooves at intervals. As shown in Fig. 11, the preferred form is the conical form hereinbefore described; but the ironers on one shaft are arranged in one direction, and those on the next shaft are arranged in the opposite direction, and this alternate arrangement is found to produce the most satisfactory results. From this ironing device the thread next passes up and through another tension device like that already explained, thence up through another ironing device like that already described, and thence up through another tension device like that already described, and thence up through another twisting device like that already described, all as shown in Fig. 10, and thence to a winding device (shown in Figs. 2, 3, 7, and 10,) which I will now describe. A pulley 20, mounted upon a standard 21 on the top of the machine, is driven by a belt 19 from a pulley 18, as shown in Fig. 10. The pulley 20 rotates the shaft 165. This shaft has a number of whirls 166 thereon. It is mounted on bearings 167 168 on standards 169 170 on the top of the frame of the machine. At the ends of the shaft 165 are the beveled gears 171 and 172. A beveled gear 173 is mounted on a shaft 174, which is supported in bearings 175 of the standard 170, and at the ends of the shaft 174 are crank-arms 176 177. A beveled gear 178 is mounted on a shaft 179, which is supported in bearings 180 181 of the standard 169, and at the ends of the shaft 179 are crank-arms 182 183. On a rail 184 are mounted spindles 185, which 100 spindles are supported midway their length by the rail 186. Each spindle 185 has a whirl 187, and a band or belt 188 from the whirls 166 to the whirls 187, respectively, rotates each spindle 185. Each spindle 185 carries a spool 189, loosely mounted thereon. A traverse-rail 190 has thread-eyes 191, and the thread passes from the upper twisters through the eyes 191 and is wound on the spool 189. The traverse-rail 190 has a guide-rod 192 bolted thereto at 193 on each end, which guide-rod 192 passes through a vertical longitudinal opening 194 in a standard 195 at each end of the machine. A link 196 is loosely mounted on a block at the inner end of the rod 192 and is pivotally connected at its outer end to the crank-arm 177. Thus the rotation of the pulley 20 turns the shaft 165 and the beveled gears 171 172 thereon, and these beveled gears turn the beveled gears 173 178, 105 which rotate their respective shafts 174 179 and carry around the crank-arms 177 183, re-

spectively. The crank-arm 177 is connected pivotally with the link 196, and as the crank-arm 177 describes its circle it forces by the link 196 the traverse-rail 190 to alternately 5 rise and descend, and thus the thread is wound regularly upon the spools 189. A similar construction is at the other three connections of the traverse-rails 190 and needs no description. The speed of the spooling 10 can be controlled by cone-pulleys, as illustrated in Fig. 7.

By dividing the trough 24 into sections by cross-partitions as many compartments may be made as desired, and in each compartment 15 may be placed a different dye liquid, so that threads of different colors can be finished at the same time, and it is evident said trough or its compartments may be filled with liquid dye or with liquid sizing, as may be preferred.

The levers 28 enable the operator to immerse the thread in the dye liquor or sizing without soiling or wetting his hand.

By means of the shipping-lever 46 the 25 twisting mechanism can be at any time thrown into or out of engagement, and each set or series of twisters is independent of the others.

The rollers 70 71 thoroughly work the dye liquor or sizing into the thread as it is being 30 twisted. By the slot arrangement shown in Figs. 14 to 18, inclusive, it is apparent that the thread is easily inserted or taken out of the twisters, and that when a thread breaks or runs out it can easily be tied and replaced 35 without stopping any other set of twisters.

By the tension devices the fineness of the thread can be regulated, the more tension the finer, the less tension the coarser the thread. By adjusting the tension bars and wheels the 40 degree of angular deflection of the thread is determined. It is evident, therefore, that this machine can finish threads of different grades and sizes at the same time.

The greater speed of the rotation of the 45 brushes than that of the cylinders between which they are mounted enables the proper laying of the fibers of the thread as the thread passes angularly over each brush in turn, as illustrated in Fig. 10.

50 The steam heat in the brush-cylinders and in the brush-shafting enables the rapid drying of the thread.

In the ironing device the thread is subjected to great heat from the steam which 55 passes through the cylinders and pipes. Each ironer is hot, and each row of ironers on a shaft revolves more rapidly than the steam-cylinders between which said ironers and shafts are mounted. This rapid rotation of 60 the ironers gives the thread a high gloss and superior finish. By the conical shape of the ironers and their alternate arrangement the thread is finished round and is not flattened, as might more or less be the case if the surfaces of the ironers were not inclined to each 65 other, as specified.

My improved machine is made much more

compact than those of the same capacity, but otherwise constructed.

The mechanism is simple and easily oper- 70 ated.

I claim as a novel and useful invention and desire to secure by Letters Patent—

1. In a thread-dressing machine, the combination of a trough, a rod properly mounted, a lever centrally mounted loosely on said rod and having a chambered hub provided with a kerf on its edge, a fixed collar on said rod and provided with a wedge-shaped projection capable of engagement with said kerf, 80 a second fixed collar on said rod and provided with a tubular projection which enters said chambered hub, a spiral spring in the chambered hub surrounding the rod and bearing against the projection of the second-named 85 collar, and a grooved wheel at the lower end of said lever, substantially as described.

2. In a thread-dressing machine, a twister consisting of a vertical shaft properly mounted and having two parallel standards extending up from the upper end thereof, means adapted to rotate said shaft, a beveled gear secured to a horizontal shaft which is mounted in said standard, a roller fastened upon said horizontal shaft and a second roller mounted 95 loosely in said standards and rotatable by friction of the first-named roller and suitable thread-guides, in combination with a fixed beveled gear upon another support in engagement with the first-named beveled gear, said last-mentioned beveled gear and said vertical shaft being radially slotted to allow the passage of a thread to its geometrical center, and means adapted to prevent said thread from leaving said slots, substantially as specified. 105

3. In a thread-dressing machine, the combination of a bracket or frame having a tubular bearing, and provided with a V-shaped radial opening at its bottom, a beveled gear fixed upon said tubular bearing and having in 110 its hub a central bore in line with the bore of said bearing, a sleeve or tube loosely mounted in the bores of said beveled gear and bearing and provided with a longitudinal slot and with a handle which projects through the radial opening aforesaid, a vertical shaft having 115 a radial longitudinal slot and mounted rotatably in said tube or sleeve, a gear upon the lower end of said vertical shaft, a circular disk integral with said vertical shaft upon the upper end thereof, which disk has a radial slot and rests upon the web of said fixed bevelled gear, two parallel standards extending up from said disk and integral therewith, which standards have a horizontal slot ex- 125 tending on one side inwardly, a horizontal shaft rotatably mounted in bearings in said standards, a roller fastened on said horizontal shaft, a beveled gear on the end of said horizontal shaft and in mesh with the fixed 130 bevelled gear, a second roller mounted rotatably in the slots of said standards and in frictional contact with the first-named roller, a thread-guide on the top of said standards, and

gearing rotated by power in mesh with the gear at the bottom of said vertical shaft, substantially as shown.

4. In a thread-dressing machine, the combination of two steam-cylinders rotatable and mounted on a hollow shaft which is adapted to discharge steam therein, a plurality of steam-pipes mounted rotatably at their ends respectively in said steam-cylinders and opening therein, a cylindrical brush fixedly mounted on each of said steam-pipes, means adapted to rotate said steam-cylinders and means adapted to rotate each of said brushes and the hollow shafts thereof, substantially as set forth.

5. In a thread-dressing machine, the combination of two steam-cylinders mounted upon a hollow shaft which is adapted to discharge steam therein, means adapted to rotate said steam-cylinders at the same speed, a plurality of steam-pipes mounted at their ends respectively in said steam-cylinders and opening therein, a cylindrical brush fixedly mounted on each of said steam-pipes, and means adapted to rotate each of said brushes and the hollow shafts thereof at a greater speed than that of the said steam-cylinders, substantially as described.

6. In a thread-dressing machine, the combination of a frame, two brackets secured upon the frame and each having a tubular bearing, two steam-cylinders one of which has a short tubular hub and the other of which has a long tubular hub mounted in one of said bearings, a pulley on said long cylinder-hub and adapted to be rotated by a belt, a tubular shaft connecting said two steam-cylinders, a shaft contained in the tubular shaft last named and having its center solid but its two ends tubular with each of said tubular ends provided with a hole adapted for the passage of steam between it and the adjacent steam-cylinder, a plurality of tubular shafts mounted rotatably in said two steam-cylinders and each opening at or near its ends into said two steam-cylinders, a cylindrical brush fixedly mounted on each of said tubular shafts, a pulley having a long tubular hub by which it is mounted rotatably in the other of said bearings and through which one of the tubular ends of the second-named shaft extends, which pulley-hub enters into the adjacent steam-cylinder, a belt to rotate the last-named pulley, a gear upon the inner end of said pulley-hub and fastened thereto, a gear having a diameter less than that of the last-named gear fastened upon the end of each of said plurality of tubular shafts of the brushes and engageable with the gear which is upon the inner end of said pulley-hub, and a steam-pipe connected with each tubular end of the second-named shaft, substantially as specified.

7. In a thread-dressing machine, the combination of two rotatable disks mounted upon a proper support and a plurality of rollers mounted at their ends respectively on said

disks, ironers having tubular hubs by which they are mounted fast on said rollers, respectively, means to rotate said disks, and means to rotate said rollers, substantially as shown.

8. In a thread-dressing machine, the combination of two steam-cylinders rotatable and mounted on a tubular shaft which is adapted to discharge steam therein, a plurality of tubular shafts mounted rotatably at their ends in said steam-cylinders and opening therein, ironers having tubular hubs by which they are mounted fast on said tubular shafts last aforesaid, respectively, means adapted to rotate said two steam-cylinders and means adapted to rotate said last-named tubular shafts, substantially as set forth.

9. In a thread-dressing machine, the combination of two steam-cylinders rotatably mounted on a tubular shaft which is adapted to discharge steam therein, means adapted to rotate said two steam-cylinders at the same speed, a plurality of tubular shafts mounted rotatably at their ends in said steam-cylinders and opening therein, ironers having tubular hubs by which they are mounted fast upon said tubular shafts last aforesaid, respectively, and means adapted to rotate each of said ironer-shafts at a greater speed than that of the said steam-cylinders, substantially as specified.

10. In a thread-dressing machine, the combination of a frame, two brackets secured upon said frame and each having a tubular bearing, two steam-cylinders one of which has a short tubular hub and the other of which has a long tubular hub mounted in one of said bearings, a pulley on said long tubular hub and adapted to be rotated by a belt, a tubular shaft connecting said two steam-cylinders, a shaft contained in the tubular shaft last aforesaid and having its center solid but its two ends tubular with each of said tubular ends provided with a hole adapted for the passage of steam between it and the adjacent steam-cylinder, a plurality of tubular shafts mounted rotatably in said two steam-cylinders and each opening at or near its ends into said two steam-cylinders, ironers having tubular hubs by which they are mounted fast upon the tubular shafts last aforesaid, respectively, a pulley having a long tubular hub by which it is mounted rotatably in the other of said bearings and through which one of the tubular ends of the second-named shaft extends, which pulley-hub enters into the adjacent steam-cylinder, a belt to rotate the last-named pulley, a gear upon the inner end of said pulley-hub and fastened thereto, a gear having a diameter less than that of the last-named gear fastened upon the end of each of ironer-shafts and engageable with the gear which is upon the inner end of said pulley-hub, and a steam-pipe connected with each shaft, substantially as specified.

11. In a thread-dressing machine, the combination of thread-twisting, thread-brushing, thread-ironing and thread-winding devices,

with a traversing mechanism for the thread-winding means consisting of a horizontal traverse-rail having thread-eyes contiguous to the winding-spools, a driving-pulley deriving motion and power from the main shaft of the machine, a shaft properly mounted and rotated by said pulley, a beveled gear mounted on each end of said shaft, a traverse-shaft mounted at each end of the machine, a beveled gear on each traverse-shaft meshing with the first-named beveled gear, a crank-arm on the end of each traverse-shaft, a guide-rod extending from each end of the traverse-rail, two vertical standards on the

top of the machine, each provided with a vertical opening or passage through which one of said guide-rods extends, and a link pivotally connected with the end of the adjacent crank-shaft and also pivotally connected with the end of the adjacent guide-rod, substantially as specified.

In testimony whereof I affix my signature in presence of two witnesses.

GEORGE A. FREDENBURGH.
